J. W. JENNINGS.
BAG FRAME,
APPLICATION FILED MAY 24, 1915.

1,162,927.

Patented Dec. 7, 1915.

UNITED STATES PATENT OFFICE.

JAMES W. JENNINGS, OF PROVIDENCE, RHODE ISLAND, ASSIGNOR TO SAHATIEL G. MANDALIAN, OF NORTH ATTLEBORO, MASSACHUSETTS.

BAG-FRAME.

1,162,927.

Specification of Letters Patent.

Patented Dec. 7, 1915.

Application filed May 24, 1915. Serial No. 29,975.

To all whom it may concern:

Be it known that I, JAMES W. JENNINGS, a subject of the King of Great Britain, residing at Providence, in the county of Providence and State of Rhode Island, have invented certain new and useful Improvements in Bag-Frames, of which the following is a specification.

My invention relates to bag tops, or frames from which bags depend.

The essential objects of my invention are to present to the observer an unbroken contour when the bag is closed; to enable the frame to be folded and to expand; and to attain these ends in a structure which is inexpensive to construct, easy to operate, and ornamental in appearance.

To the above ends essentially my invention consists in such parts and combinations of parts as fall within the scope of the appended claims.

In the accompanying drawings which form a part of this specification, Figure 1 is a front elevation of my bag frame attached 25 to a bag, Fig. 2, an enlarged plan elevation of the frame in folded or closed position with the cover raised, Fig. 3, a similar elevation of the same expanded, and the cover broken away, Fig. 4, a side elevation of the 30 portion of the frame at and adjacent the joint of the expanded frame, Fig. 5, a section on line 5—5 of Fig. 3, Fig. 6, a section on line 6—6 of Fig. 3, Fig. 7, a section on line 7—7 of Fig. 6, and Fig. 8, a central 35 transverse section of the frame.

Like characters of reference indicate like parts throughout the views.

In detail the frame comprises two body plates A, A', of similar form, and in the 40 present instance semi-elliptical, so that their end portions a, a' abut against each other and form a complete ellipse when the bag is closed, as shown in Fig. 2. These body plates may be polygonal rather than oval if preferred. They are respectively provided at 45 the upper outer margins with grooves or cut away portions b, b', to afford a seat for the cover. To opposite ends a and a' of the body plates are fixed suspension rings C and C' respectively.

Attached to an intermediate portion of the plate A by a hinge D is a cover E whose downwardly extending marginal flange e seats in the grooves b, b'. A spring F on the

hinge pindle f engages the body plate and 55 cover, normally holding the parts distended.

Pivotaly connected with inner faces of the portions a of the body plate A, near the ends thereof, are side plates G, G. Similar plates G', G' are pivotally connected at corresponding points to the portions a' of the plate A', and each plate couplet G and G' is pivotally connected at its inner end to permit folding toward each other when the body plates A and A' are compressed. 65

In the present instance the hinges H forming the pivotal connection of the side plates with each other comprise in each case hinge sleeves i upon the plate G, embracing a hinge sleeve i' upon the plate G', and a pindle j 70 passing through the sleeves, as shown in Fig. 4. It will be noted by reference to Fig. 3 that the sleeves i and i' are seated in curved cavities k and k' formed in the outer faces of the plates G and G' and extending 75 partially along the end faces of these plates, so that while the plates are free to fold inwardly, they are checked against outward movement beyond alinement by virtue of the contact of their adjacent end faces. 80

The pivotal connections of the plates G with the plate A consist of the hinges K, K; and those of the plates G' with the plate A', of the hinges K', K'. As all four hinges are of like construction a description of one 85 will serve for all. As shown in Figs. 6 and 7, the plate A has hinge sleeves l, l, embracing spaced hinge sleeves m on the plate G. The pindle n passes through all the sleeves, and surrounding this between the sleeves m 90 is a helical spring o whose opposite ends form arms o' and o'' pressing respectively against the inner faces of the plates A and G. By virtue of the springs o the folding side plates are forced out into the open position shown in Fig. 3, and in this distended 95 position articles may be inserted or removed from the bag.

In closing the body plates A and A' are manually compressed until the parts assume 100 the position shown in Fig. 2, whereupon the cover E is depressed and its flange seated in the marginal grooves b, b', where it is frictionally held. A sufficient frictional contact being assured by the action of the springs o. 105

A suspension cord or chain P, shown partially broken away in Fig. 1, is connected with the suspension rings by links or rings p.

In the present instance an ornament *q* is shown mounted in the face of the frame.

A mesh, skin, or fabric, bag *R* is attached to the described frame in any usual or convenient manner. In the present instance the end and side plates are provided with series of marginal perforations *r* to receive an attaching thread or rings.

It will be observed that the plates may be formed from blanks, and that the connecting parts are few and inexpensive. Furthermore, the location of the hinges *K* and *K'* at some distance away from the abutting edges of the body plates, affords a tight engagement of the latter, and thus disguises the fact that the apparently integral frame is jointed.

What I claim is:—

1. In an expansible bag frame, the combination of a plurality of hollow body plates arranged to form a sectional body, side plates disposed in pairs within the body,

pivot members connecting the inner ends of plates of each pair to each other, and pivot members connecting the outer ends of the side plates to different body plates, at points spaced from the ends of the body plates. 25

2. In an expansible bag frame, the combination of a plurality of hollow body plates arranged to form a sectional body, a cover 30 pivotally mounted upon one plate and engaging the other plate, side plates disposed in pairs within the body, pivot members connecting the inner ends of the plates of each pair to each other, pivot members connecting the outer ends of the side plates to different body plates at points spaced from the ends of the body plates, and springs upon the last mentioned pivot members engaging the body plates and the side plates. 35

In testimony whereof I have affixed my signature.

JAMES W. JENNINGS.
